US00D980158S

(12) **United States Design Patent** (10) **Patent No.:** **US D980,158 S**
Morad et al. (45) **Date of Patent:** **** Mar. 7, 2023**

---

(54) **SOLAR PANEL**

(71) Applicant: **SUNPOWER CORPORATION**, San Jose, CA (US)

(72) Inventors: **Ratson Morad**, Palo Alto, CA (US); **Gilad Almogy**, Palo Alto, CA (US); **Itai Suez**, Santa Cruz, CA (US); **Jean Hummel**, San Carlos, CA (US); **Nathan Beckett**, Oakland, CA (US)

(73) Assignee: **SUNPOWER CORPORATION**, San Jose, CA (US)

(**) Term: **15 Years**

(21) Appl. No.: **29/778,059**

(22) Filed: **Apr. 9, 2021**

(57) **CLAIM**

The ornamental design for a solar panel, as shown and described.

DESCRIPTION

FIG. 1 is a front, top, and right side perspective view of a solar panel.

FIG. 2 is a front elevational view thereof, the rear elevational view forming no part of the claimed design.

FIG. 3 is a top plan view thereof, the bottom plan view being a mirror image of the top plan view shown.

FIG. 4 is a left side elevational view thereof, the right side elevational view being a mirror image of the left side elevational view shown.

FIG. 5 is a detail view of the callout box 5 in FIG. 2; and, FIG. 6 is a detail view along line 6-6 in FIG. 5.

The broken lines show portions of the solar panel that form no part of the claimed design.
